UNITED STATES PATENT OFFICE.

MAXWELL M. UPSON, OF ENGLEWOOD, NEW JERSEY, AND HORACE P. HAMLIN, OF NEW YORK, N. Y., ASSIGNORS TO RAYMOND CONCRETE PILE COMPANY, OF NEW YORK, N. Y., A CORPORATION OF NEW JERSEY.

REINFORCED BULKHEAD OR RETAINING-WALL.

1,111,979.

Specification of Letters Patent. Patented Sept. 29, 1914.

Application filed December 20, 1910. Serial No. 598,426.

To all whom it may concern:

Be it known that we, MAXWELL M. UPSON and HORACE P. HAMLIN, citizens of the United States, residing, respectively, at 5 Englewood, county of Bergen, and State of New Jersey, and in the borough of Manhattan, New York city, State of New York, have invented certain new and useful Improvements in Reinforced Bulkheads or Retaining-Walls, of which the following is a 10 full, clear, and exact description.

This invention pertains to reinforced concrete construction of bulkheads or retaining walls, and has for its object the production of a relatively cheap, simple and permanent structure, yet one that is of high efficiency and of special adaptability to certain conditions that are frequently met with in the building of docks and bulkheads. 15 The invention consists in the parts and appurtenances exemplified in the accompanying drawings and in the following description:

Figure 1 represents our invention in vertical section, in its relation to the shore and bed of a stream or other body of water. Figs. 2 and 3 illustrate details in alternative form. Figs. 4 and 5 indicate alternative form of the retaining wall proper. 20 Fig. 6 shows a modification of or addition to the bulkhead as a whole.

Assuming the conditions shown in Fig. 1, which shows the shore level, the bottom level and the water level of a stream, we first 25 drive a series of reinforced concrete piles A, preferably provided with two series of reinforcements, as a' , running longitudinally, and a , running horizontally. The horizontal reinforcements a may be made to 30 extend beyond the rear, or shore-ward face of the piles in the upper half thereof, as shown.

While we prefer to pre-mold the piles A and drive them to the position shown, they 35 may be formed *in situ* in any of the well known ways. The depth to which the piles are to be driven or built into the river-bed will depend, of course, to a large extent upon the nature of its soil and of that of the

river-bank, but in general, they should be 50 driven a distance at least equal to the height of the river-bank above the solid bottom-level of the water. On the water side of each pile, and preferably at the solid ground level—which may of course be the actual bottom of the stream or of the hard bottom below any accumulation of mud or silt—we place a mass D of bowlders or grouting, or the like, so that each pile or pillar A is, structurally speaking, a vertical cantaliver. 55 This mass, D acts to increase the bearing power of the earth at the fulcrum of the cantaliver piles.

On the shore side of the series of piles and extending from pile to pile we build a 60 wall composed of reinforced concrete slabs B, the reinforcements of which include, preferably, a series of metal rods b , which extend horizontally at intervals across the water side or face of the slabs. These slabs B 65 are preferably arranged as indicated in Fig. 3—that is, their ends do not quite meet at the back of the piles A, but leave a vertical space E. The metal reinforcements b should be of sufficient length to extend beyond the 70 opposed faces or ends, and they, like the horizontal reinforcements a of the piles may be bent backward so as to extend out on the shore side of the structure, opposite the piles A (Fig. 2). Then we fill the space E 75 between the opposing end of the slabs B with grouting or concrete, which is also filled in to a space on the shoreward side of the slabs B and opposite the pile A, as shown in Fig. 2, so as to encompass the projecting reinforcements of slabs or piles or both. The structure is now complete, although it may, if desired, be provided with a horizontal beam G, as shown in Fig. 6, composed of concrete united to the piles A 80 and slabs B by the extension of the metal reinforcements, and, if desired, one or more of the piles A may be provided with a tie beam F connecting it with a rear anchorage H, (see Fig. 6), which may all be composed of concrete and united with the piles A, as by the extension of the metal reinforcements, into a single integral structure, 85 90 95

or the tie beam F and anchor H may be of wood or metal, if desired.

The slabs B, which constitute the retaining wall proper, are preferably pre-molded and may be either flat as indicated in Figs. 2 and 3, or arch shaped, as indicated in Fig. 5, or, if desired, they may be sectional, as indicated in Fig. 4, the sections being either pre-molded and formed with interlocking means as there indicated, or molded in place in a manner well understood in this art.

Instead of the scheme of interlocking reinforcements indicated in Fig. 2, the piles A may be provided with a series of rearwardly extending bars or bolts e, one end of which is embedded in the concrete pile and the other end projects sufficiently far rearwardly so that when provided with screw thread, a flat plate or washer f and nut g it may serve, by these means, to lock together the pile A and the slabs B, B, the space E intervening the abutting ends of the slabs being filled with grouting or concrete, if desired, as in Fig. 2.

25 It will be readily understood that a structure embodying our invention is a watertight wall, capable of being used either as a bulkhead or as a retaining wall for any purpose.

26 What we claim as our invention is:

1. A bulk-head consisting of a series of reinforced concrete piles, each driven into the solid earth and provided with an abutment situated at substantially the earth's 35 level, and a series of reinforced concrete slabs extending from pile to pile, the slabs and piles being provided with one or more series of projecting reinforcements, and means for integrally uniting said piles and 40 said slabs through said projecting reinforcements.

2. A bulk-head or retaining wall comprising a series of reinforced concrete piles placed at intervals, a series of reinforced concrete slabs each extending from pile to pile and partially overlapping said piles, reinforcements extending from said slabs rearwardly and a concrete structure integrally uniting said slabs, said piles and said 55 projecting reinforcements.

3. A bulk-head or retaining wall comprising a series of piles set at intervals, a slab formation extending from pile to pile, each slab being in arched form, metal reinforcements embedded in said piles and projecting rearwardly of said slabs and means for integrally uniting said reinforcements to said slabs.

4. A bulk-head or retaining wall comprising a series of piles set at intervals, a slab formation extending from pile to pile, each slab being in arched form, and comprising a series of interlocking units, metal

reinforcements embedded in said piles and projecting rearwardly of said slabs and 65 means for integrally uniting said reinforcements to said slabs.

5. A bulk-head or retaining wall, comprising a series of piles of cantaliver construction and arrangement set at intervals, a slab formation extending from pile to pile, each slab being in arched form, metal reinforcements embedded in said piles and projecting rearwardly of said slabs and means for integrally uniting said reinforcements to said slabs.

6. A bulk-head or retaining wall, comprising a series of piles of cantaliver construction and arrangement set at intervals, a slab formation extending from pile to pile, each slab being in arched form, and comprising a series of interlocking units, metal reinforcements embedded in said piles and projecting rearwardly of said slabs and means for integrally uniting said reinforcements to said slabs.

7. A bulk-head or retaining wall consisting of a series of piles set at intervals, a slab formation extending from pile to pile, metal reinforcements embedded in said piles and projecting rearwardly of said slabs, means for integrally uniting said reinforcements to said slabs, a tie beam integrally united with one or more of the piles and extending rearwardly and an anchorage 90 supporting the earth end of each tie beam.

8. A bulk-head or retaining wall consisting of a series of piles set at intervals, a slab formation extending from pile to pile, metal reinforcements embedded in said piles and projecting rearwardly of said slabs, means for integrally uniting said reinforcements to said slabs, a tie beam integrally united with one or more of the piles and extending rearwardly, an anchorage supporting the earth 105 end of each tie beam, and a horizontal beam resting upon said piles and slabs and integrally united therewith by metal reinforcements.

9. A bulk-head or retaining wall consisting of a series of piles of cantaliver construction and arrangement, composed of reinforced concrete and a slab formation comprising premolded slabs extending from pile to pile composed of reinforced concrete and 115 united at the piles to form a tight construction.

10. A bulk-head or retaining wall consisting of a series of piles of cantaliver construction and arrangement, composed of reinforced concrete and a slab formation extending from pile to pile composed of reinforced concrete forming a tight construction, and means for increasing the bearing power of the earth at the fulcrum of the 120 cantaliver.

11. A reinforced concrete bulk-head or retaining wall consisting of vertical, cantilever acting piles, a slab formation retained by said piles and a horizontal beam tying said slabs and piles together forming a tight construction.
